OF NEW YORK, N. Y., A CORPORATION OF NEW YORK.

FEEDING DEVICE FOR ROASTING-FURNACES.

1,102,454.

Specification of Letters Patent.

Patented July 7, 1914.

Application filed March 7, 1913. Serial No. 752,538.

To all whom it may concern:

Be it known that I, HARRY H. STOUT, a citizen of the United States, and a resident of the borough of Manhattan, city, county, and State of New York, have invented a new, useful, and Improved Feeding Device for Roasting-Furnaces, of which the following, taken in connection with the accompanying drawings, is a specification.

10 My invention relates to roasting furnaces, especially such as are used for roasting pyrites or other ores, and such as are provided with stationary hearths upon which the ore is stirred and distributed by rakes or plows affixed to rotating arms, and has for its principal object the provision of means whereby the ore may be fed to the furnace automatically and in regulatable quantities.

20 Further objects will be pointed out or will otherwise appear in the following description of the embodiment of my invention shown in the accompanying drawings, which illustrate my invention as applied to a roasting furnace of the well known type such as is shown and described, for instance, in the patent to John B. Francis Herreshoff, No. 976,175, dated November 22, 1910, and in which—

30 Figure 1 is a vertical section of a portion of the furnace equipped with my improved feeding mechanism, the section passing through the secondary feeding device and Fig. 2 is a plan view of a diametral portion thereof, the primary hopper being removed.

The furnace illustrated comprises a cylindrical structure surrounded by a casing 1 and provided with a series of superposed floors, of which three only are shown and indicated in Fig. 1 by the reference characters 2, 3 and 4, the floors being alternately provided with peripheral apertures, as 3' and central apertures, as 2' and 4'. The upper floor 2 constitutes a roof for the furnace and 40 is utilized as a hearth for supporting and drying the ore before it is fed to the burning hearths formed by the floors 3 and 4 and the other floors within the furnace.

Extending vertically through the furnace 50 is a rotatable double walled shaft 5 to which is affixed a plurality of horizontally extending stirrer arms or rabble arms 6, 7 and 8. The arms, 6, which are preferably four in number, extend over the top or roof 2 and 55 are provided with suitable plows or de-

flecting teeth 6' which extend into the ore to agitate it and move it gradually toward the axis of the furnace during the rotation of the shafts. The ore thus impelled finally falls through the aperture 2' into the hopper 60 of the secondary feeding device to be herein-after described and upon issuing from said device falls upon the floor 3 upon which it is stirred and deflected toward the opening 3' by the angularly arranged teeth of the 65 rabble arms 7. After discharging through the opening 3' upon the hearth 4, the ore is deflected in a similar manner by means of the teeth of the rabble arms 8 toward the opening 4' in said hearth. Thus the ore is 70 caused to traverse all the hearths of the furnace, its oxidation being accomplished during its passage, and is finally discharged fully roasted, at the bottom of the furnace. The products of combustion pass in an opposite direction and finally issue through suitable passages at the upper portion of the furnace.

75 The rabble arms are each provided with a passage which is in communication at one 80 end with the interior of the inner wall of the shaft 5, the other end being in communication with the annular space between the inner and outer walls of said shaft. This 85 annular space is in communication with the dampered stack 9. With this construction it is obvious that a circulation of cooling air may be established for the purpose of cooling the rabble arms. The shaft 5 is journaled in suitable lower and upper bearings, 90 the latter of which is shown and indicated by the reference number 10 and is supported on I-beams 11 which extend across the top of the furnace above the top 2.

95 The hopper 12 of the primary feeding device may be of any suitable construction and is supported upon the beams 11, near the outer edge of the furnace. The ore to be treated is fed to the hopper 12 in any well known manner and discharges from the 100 office thereof upon the support 13 which may be a part of the bracket 14 supporting one end of the beams 11. The bracket 14 forms a back which prevents the ore from discharging externally of the casing 1. The 105 support 13 is provided with an extension 15 adjustably secured to the support by bolt-and-slot connections so that it can be fastened in a variety of positions to extend the inner edge of the support 13 to a greater or 110

less degree toward the center of the furnace and thus vary the area of the support. The position of adjustment of this edge depends in usual practice upon the talus angle, or 5 angle of repose, of the pile of ore discharged from the hopper 12 and this, in turn, depends upon the nature of the ore or the condition thereof, such as its dampness or the fineness of its particles. Generally it is preferable to adjust this edge so that the base 10 of the pile of ore whatever the angle of repose may be, is barely supported by the shelf 13 the result being that a slight disturbance of the pile will precipitate a part 15 of the ore over the edge upon the roof 2. It will readily be seen that with such an adjustment only a very small amount of power is required to remove the ore from the support. It is to be understood however, that 20 the edge may be adjusted nearer to or farther from the axis of the furnace.

Rising from one or more of the rabble arms 6 and near the outer extremities thereof is a wiper support 16, the upper portion 25 of which is provided with an aperture angularly disposed with reference to the longitudinal axis of the arm and through this aperture extends a horizontally disposed wiper 17 which, during the rotation of the 30 rabble arm, sweeps above the support 13. The wiper is adjustably held in position in the wiper support, in an obvious manner by a set screw 18 and, as will readily be understood, may be set to sweep over any desired 35 area of the support 13, so as to disturb and dislodge any desired portion of the pile of ore on said support. Owing to the angular position of the wiper, in which its outer extremity is forward of the arm, the rotation 40 being in the direction of the arrow on Fig. 2 of the drawings, the ore is propelled in a direction generally toward the center of the furnace and is thus caused to fall over the edge of the support 13 upon the top of the 45 furnace therebelow. As shown in Fig. 2, the wiper 17 on one of the arms 6 is followed by a wiper 17' on another arm; the two wipers may be similar or may vary as to active area or as to the degree of projection over 50 the support 13, as may be desired, it being understood, however, that a single wiper may be successfully used.

The teeth 6' of the rabble arms 6 gradually move the ore along the roof 2, the ore 55 being dried meanwhile, toward the axis of the furnace until it falls through the aperture 2' into the hopper 19 of the secondary feeding device. This hopper is annular in form and is secured at its inner portions to 60 the shaft 5 so as to rotate therewith. The periphery of the hopper extends under a depending annular collar secured within the aperture 2' in the roof 2, so that the ore passing through said aperture must fall into 65 the hopper, the hopper making a sealable

joint with said roof and the ore in the hopper being the medium for sealing said joint. The bottom of the hopper is provided with a depending spout 20, through the orifice of which the ore is fed from the hopper upon 70 the support or hearth 3. The spout 20 is provided with a telescopic extension 21 which is vertically slidable with reference to the fixed portion of the spout so that the distance between the hearth 3 and the discharge orifice of the hopper may be varied. In order to insure a ready and accessible 75 adjustability of the extension 21, I have provided a member 22 secured at its lower end to said extension and screw threaded at 80 its upper end, the screw threaded portion extending through a bracket 23 suitably supported in one of the arms 6 and being engaged thereabove by a handle-nut 24. It will be readily understood that manipulation 85 of the nut will result in the raising or lowering of the extension 21. The extension extends between adjacent rabble arms 7 but is not interfered with by them because the feeding device rotates at the same speed 90 as the rabble arms.

If there were no movement of the parts the ore discharged by the secondary feeding device would form a conical pile upon the support or hearth 3, which would increase 95 in size until it closed the orifice of the device. In the operation of the furnace, however, the feeding device moves in a circular path, the hearth 3 being, of course, stationary, with the result that the ore is distributed upon the hearth. This ore is continually being moved toward the aperture 3' by the teeth of the rabble arms 7, so that when properly operated there is a continuous discharge from the orifice, while at the 100 same time the hopper spout is at all times filled with ore and gaseous products are prevented from escaping therethrough.

The employment of primary and secondary feeds of the kind described insures a 110 proper and controllable introduction of ore to the furnace. The primary feed is adjustable so that it can be accommodated to ores of varying characteristics and, whatever the ore, any given quantity, within limits, of 115 course, can be fed. The feeding is in this case intermittent while in the case of the secondary feeding device, it is continuous. In both cases, however, the feeding is controllable and regulatable; by coöperation 120 of the two adjusted devices a proper and delicately variable amount of ore is capable of being introduced into the furnace.

I claim:

1. A feeding device comprising a hopper 125 provided with a discharge orifice, a support below said hopper and spaced from said orifice, said support being variable in area and adapted to receive and support the material discharged from said hopper, and

means for removing a portion of said material from the support.

2. A feeding device comprising a support, a hopper provided with a discharge orifice spaced above said support whereby material may be discharged from said orifice to form a pile upon said support until the pile thus formed closes said orifice, said support being adjustable in area to accommodate materials of varying angles of repose, and means for removing a portion of the material from said pile.

3. In a roasting furnace, the combination of a plurality of stationary floors, a rotatable shaft extending through said floors, an annular hopper secured to and surrounding said shaft and making a sealable joint with one of said floors, said hopper having a discharge orifice spaced above the other of said floors, and means for feeding material into said hopper.

4. In a roasting furnace a stationary top and a stationary hearth therebelow, the combination of an adjustable primary feeding device for feeding ore to the top, an adjustable secondary feeding device secured to a movable part of the furnace and provided with an orifice spaced above and adapted

to move over said hearth for feeding ore to and distributing it upon said hearth, and means for feeding to the secondary device the ore discharged from the primary device.

5. In a roasting furnace having a stationary top and a stationary hearth therebelow, the combination of an adjustable primary feeding device for feeding ore to the top, an adjustable secondary feeding device for feeding ore to the hearth, said secondary device being provided with a discharge orifice spaced above said hearth, means for supporting said secondary device and moving it in a direction such that the distance between said orifice and said hearth is maintained substantially constant, whereby the ore discharged by said secondary device is distributed upon said hearth, and means for feeding to the secondary device the ore discharged from the primary device.

In testimony whereof, I have hereunto set my hand in the presence of two subscribing witnesses.

HARRY H. STOUT.
